MANUEL GODINEZ, OF CHICAGO, ILLINOIS, ASSIGNOR TO GIFFORD-WOOD COMPANY, OF
HUDSON, NEW YORK, A CORPORATION OF NEW YORK

GRAVITY CHUTE

Application filed January 25, 1929. Serial No. 334,966.

This invention relates to gravity chutes and, among other objects, aims to provide an improved spiral chute that can be manufactured very cheaply and that is designed to prevent spillage and consequent breakage of coal or other material during its descent. Also, it contemplates an improved feed hopper having provision to discharge material directly on the pile after the top of the pile has choked up the chute, to increase the volume of material that a chute can handle and obtain the maximum benefit of the available storage space.

In the accompanying drawings,

13 Fig. 1 is a side elevation of a chute embodying the invention;

Fig. 2 is a top plan view of the chute;

20 Fig. 3 is a sectional view taken on the line 3—3 of Fig. 1;

Fig. 4 is a fragmentary top plan view, on an enlarged scale, showing the upper convolution of the chute;

Fig. 5 is a lower end elevation of the uppermost section of the chute;

25 Fig. 6 is an upper end elevation of the uppermost section;

Fig. 7 is a lower end elevation of one of the other chute sections;

Fig. 8 is an upper end elevation of the chute section shown in Fig. 7;

Fig. 9 is a top plan view of the feed hopper;

Fig. 10 is a side elevation of the hopper;

25 and Fig. 11 is a rear elevation of the hopper;

Fig. 12 is a sectional view taken on the line 12—12 of Fig. 9.

Referring particularly to the drawings, the improved spiral chute there shown includes a series of cast metal convolute sections 10 each having an outside flange 11 and radial end flanges 12 adapted to be secured one to the other. No inside flange is necessary because, as the material ac-

quires speed, its centrifugal force will prevent it from falling into the core portion. Herein, each section is shown as forming a quarter of a complete convolution and the abutting radial end flanges 12 are secured to four uprights 13 by means of the same

bolts or rivets that secure the sections together. All of the sections except the top one are preferably duplicates so that they can be used interchangeably.

The uprights 13 are conveniently made of structural angles first secured together or braced by spiders 14 at the upper and lower ends of the chute, and at intervals they are also braced by suitable tie rods 14^a. Brace rods 15 (Fig. 1) may also be used to brace the uprights to a bin wall or the like. The lower ends are adapted to be anchored in any convenient manner to the bottom of a bin or a pocket or on the storage surface.

The upper section of the chute, designated 10^a, is shown as being U-shaped, having both inner and outer vertical flanges, the idea being to prevent the escape of material as it starts down and before it acquires very great speed. The bottom of this section is substantially the same height at the inside of the chute as it is at the outside. However, at the lower end, the inside portion is sharply inclined, as shown at 16, so that its end edge is flush with and conforms to the upper edge of the next lower section 10, the bottoms of the chute sections below being inclined radially and inwardly, to distribute the falling material more or less evenly over the bottom. The idea of this sharply inclined portion is to

give the material at the inner edge of the chute a sharply accelerated start so that it will not spill or run out inside the core portion. Otherwise, the material would not acquire sufficient centrifugal force to resist its tendency to roll inwardly off the radially inclined bottoms of the upper sections. Moreover, the upper section transfers a uniform flow of material to the next lower chute section gradually changing or modifying the direction of flow.

The material is adapted to be guided into the upper chute section 10^a from a hopper 17, preferably made of sheet metal and having an inclined bottom 18 (Figs. 1, 10 and 12) by means of a trough section 19, the hopper being supported on top of two uprights at one side by a suitable cross bar 100

20. It is understood that the source of supply may be an ordinary conveyor or bucket well known in the art.

Now, the chute is effective to build up a pile of material until the peak chokes up the upper chute sections. To further increase the volume in the pile, the inclined bottom wall of the hopper has a hinged trap door 21 adapted to swing downwardly from the top (Figs. 10 and 11). Herein, the chute bottom has an integral angular flange 22 to which the hinges of the door and the bar 20 are secured. This flange also acts as a door stop (Fig. 10) so that the door when swung open will guide the material to fall some distance from the top of the pile. This door is shown as having an eye 23 to which a flexible pull element 24 such as a rope or chain is attached, to hold in closed position. Herein, the pull element is guided over a pulley 25 and is adapted to extend to any convenient place, so that it may be released when desired. Thus, additional material may be guided through the hopper to fall on the back side of the pile near the peak so that it will roll down the side thereof and build up a thick new layer extending from the bottom. This method utilizes the material already deposited or piled to break the fall of the rest.

From the foregoing description it will be understood that the improved chute is very simple to make and assemble. Only two kinds of castings are required to build the whole spiral and the supporting members are ordinary structural members. Moreover, the described construction and arrangement of the chute sections has demonstrated that it will reduce spillage and consequent breakage of coal to a minimum. Also, due to the initial acceleration of the material, the capacity of the chute is greatly increased.

Obviously, the present invention is not restricted to the particular embodiment thereof herein shown and described. Moreover, it is not indispensable that all the features of the invention be used conjointly, since they may be employed advantageously in various combinations and sub-combinations.

What I claim is:—

1. A lowering chute of the character described comprising a plurality of uprights; a series of convolute flanged, chute sections, placed end to end and secured together and each secured at the opposite ends to two of the uprights and presenting bottom walls inclined inwardly and downwardly; the convolute chute sections together providing a helical chute whose outer edge is provided with an upstanding flange for guiding the material and to aid in attachment of the several chute sections within the uprights; and braces secured to the uprights and ex-

tending substantially horizontally in two directions crosswise of the chute and free of the chute sections.

2. In a spiral gravity chute of the class described, a flanged feeding chute section having a bottom wall sharply inclined downwardly to give the material near the inside edge of the chute a high initial falling speed to prevent spillage over the inside edge of the chute; the sharply inclined portion of the bottom wall being generally triangular in plan and widest at the inside, narrowing toward the outside.

3. A feeding chute section for spiral gravity chutes comprising a longitudinally curved member having longitudinal, marginal, substantially vertical flanges and a bottom inclined downwardly toward one end; said bottom having a warped surface at its lower end, said surface extending laterally across the chute section and being more sharply inclined downwardly than the bottom and of greatest width at the inside edge of the chute section so as to give material at the inside of the chute an increased initial acceleration as it flows downwardly.

4. A gravity chute of the class described comprising, in combination, a supporting frame adapted to be anchored at the bottom; a series of convolute chute sections supported by the frame; a feed hopper secured to the frame and having an inclined bottom discharging into the chute; and a door in the bottom adapted to be opened to discharge additional material on the pile after the peak of the pile has reached the top of the chute.

5. A gravity chute of the class described comprising, in combination, a supporting frame adapted to be anchored at the bottom; a series of convolute chute sections supported by the frame; a feed hopper secured to the frame and having an inclined bottom discharging into the chute; a door in the bottom adapted to be opened to discharge additional material on the pile after the peak of the pile has reached the top of the chute; and remote control means connected to operate the door.

6. In combination with a gravity chute of the class described, a hopper connected to discharge into the upper end of the chute; and means to discharge material directly from the hopper after the pile chokes the upper end of the chute.

In testimony that I claim the foregoing as my own, I have hereto affixed my signature.

MANUEL GODINEZ.
